UNITED STATES PATENT OFFICE.

JOHN SVACINA AND JOHN RADL, OF MANITOWOC, WISCONSIN.

GATE FOR SWINGING BRIDGES.

SPECIFICATION forming part of Letters Patent No. 357,796, dated February 15, 1887.

Application filed November 23, 1886. Serial No. 210,673. (No model.)

To all whom it may concern:

Be it known that we, JOHN SVACINA and JOHN RADL, of Manitowoc, in the county of Manitowoc, and in the State of Wisconsin, 5 have invented certain new and useful Improvements in Gates for Swinging Bridges; and we do hereby declare that the following is a full, clear, and exact description thereof.

Our invention relates to gates for swinging 10 bridges; and it consists in certain peculiarities of construction and combination of parts, to be hereinafter described, with reference to the accompanying drawings, and subsequently claimed.

15 In the drawings, Figure 1 represents a plan view, partly in section, of a bridge provided with our gate; Fig. 2, a vertical longitudinal section through one of the bridge-abutments, showing the gate up; Fig. 3, a partial section 20 of the abutment, showing the bridge closed, both of the sectional views being taken on line x x , Fig. 1, and Fig. 4 an elevation of the abutment, showing the gate up, the bridge being open.

25 Referring by letter to the drawings, A represents an abutment, and B a swing-bridge. Operative in the frame-work of the abutment A, beneath the roadway C, is a vertical shaft, D, that has keyed thereto at its upper end a 30 rack-pinion, E, provided with a perforation, a , to engage a stud, b , on an angle-plate, F, the latter having one end thereof fulcrumed at c to a timber of said abutment, and the other end connected to a spring, G, that is in

35 turn fastened at d to another of such timbers.

The lower end of the vertical shaft D has keyed thereto a miter-wheel, e , that meshes with a similar wheel, f , on the adjacent end of a horizontal shaft, H, that also has its bearings in the frame-work of the abutment. The other end of the horizontal shaft has keyed 40 thereto a disk, I, eccentrically connected at g to a pitman, J, that in turn is connected to a vertical gate, K, operative in a slot, h , cut in the roadway.

45 The vertical edges of the gate are provided with housings i , in which are journaled anti-friction rollers j , that operate on vertical rods L , secured at their lower ends to a cross-tim-

ber, M, of the abutment, and have their upper ends terminated in brackets k , the latter being bolted or otherwise secured to the timbers N on each side of the roadway.

Each end of the swing-bridge B is provided with a rack-plate, O, to engage the pinion E 55 on the vertical shaft D, and thereby communicate motion to the horizontal shaft H, and this latter part in turn, by its disk-and-pitman connection I J, serves to operate the gate.

When the bridge is swung around away 60 from the abutment A, the rack-and-pinion-gear above described sets the shafting in motion, and thereby causes the gate K to rise above the roadway of said abutment, and by the time the rack O has passed out of mesh 65 with the pinion E the perforation or seat a in the latter will have come into register with and received the stud b on the angle-plate F, that is forced up by the spring G, and thus a lock is formed to hold said gate in its elevated 70 position and prevent the same from being forced down by accident or design. As the bridge swings home it will come first in contact with the angle-plate F, and by its weight overcome the resistance of the spring G and 75 depress said plate sufficiently to withdraw the stud b thereon from the perforation or seat in the pinion E, thus leaving the latter free for the action of the rack O, and by the time this return movement of said bridge is completed 80 the gate K will have been run down to its normal position below the roadway of the abutment.

Although we have only illustrated one end of a bridge provided with our invention, it is 85 obvious that a similar construction would be employed at the other end of said bridge.

Having thus fully described our invention, what we claim as new, and desire to secure by Letters Patent, is—

90 The combination of a swing-bridge having its ends provided with rack-plates, vertical shafts having their bearings in the bridge-abutments, pinions keyed to the shafts to mesh with the rack-plates and provided with perforations or seats, horizontal shafts geared to said vertical ones and provided with crank-disks, vertically-sliding gates arranged in said

abutments, pitmen connecting the disks and gates, and spring-plates having studs arranged to automatically engage the perforations or seats in the rack-pinion, substantially as set forth.

In testimony that we claim the foregoing we have hereunto set our hands, at Manito-

woc, in the county of Manitowoc and State of Wisconsin, in the presence of two witnesses.

JOHN SVACINA.
JOHN RADL.
